BOOM STOP FOR LOAD HANDLING MACHINES

William M. Huston, Lima, Ohio

Application July 5, 1945, Serial No. 603,378

3 Claims. (Cl. 212—59)

1

This invention relates to load handling equipment, and particularly to self-propelled load handling machines adapted to travel on crawler treads. The invention is especially concerned with a machine having an extended boom mounted for upward and downward swinging movement, for instance, a crane.

With equipment of the character mentioned above, especially a large size machine having a long boom, the boom has such mass that under certain abnormal conditions (for instance, breakage of a sling when hoisting a heavy load) the boom may tend to over-travel or swing beyond the upper limit of the normal operating range. It is a primary object of the invention to provide mechanism for limiting upward swinging movement of the boom at the upper end of the desired range of movement, which mechanism is of sturdy construction and capable of preventing over-travel of the boom under certain conditions, and to thereby avoid possible damage to the machine and minimize tendency for the machine to tilt rearwardly.

According to the structure provided by the invention, means are also provided for cushioning the motion of the boom in the upward direction adjacent the upper limit of the movement.

More particularly, the invention contemplates the employment of telescopically arranged members adapted to be extended and collapsed as the boom swings, and acting in compression upon being collapsed to limit upward swinging movement of the boom, the ends of the telescopic elements being associated, respectively, with the head of the gantry and with the boom at a point spaced appreciably from the foot end thereof, advantageously near to the center of mass of the boom.

How the foregoing together with other objects and advantages are attained will appear more fully from the following description referring to the accompanying drawings in which—

Figure 1 is a side outline view of a crane with the boom stop mechanism of the present invention applied thereto, with the boom swung downwardly to a substantially horizontal position, a portion thereof being broken out for compactness of the figure.

Figure 2 is a view similar to Figure 1 but with the boom raised to an angle approximating 48° from the horizontal, in which position the telescopic stop members are partly collapsed.

Figure 3 is a view similar to Figures 1 and 2 but illustrating the boom at the upward limit of its pivotal motion, with the telescopic stop members completely collapsed.

Figure 4 is a plan view, on an enlarged scale of the telescopic boom stops, with the telescoping parts thereof positioned substantially in accordance with the showing in Figure 3.

2

Figure 5 is a plan sectional view through one of the telescopic boom stop devices, with the parts thereof completely telescoped, as in Figure 3, Figure 5 being on a still further enlarged scale. This view has parts broken out for the sake of compactness.

Figure 6 is a view similar to Figure 5 but illustrating the telescoping parts extended.

Referring first to Figures 1, 2 and 3, the rotating base 7 of the crane there shown is mounted for swing motion on the crawler truck structure 8, the truck being provided with crawler treads diagrammatically indicated at 9, by which the machine is adapted to be propelled on the ground. The rotating base 7 serves to mount the operating machinery, including the power plant, boom hoist drums, etc., all of which machinery is housed within the cab 10. In the particular machine illustrated, the rotating base also supports the control tower 11 which is offset toward one side of the plane of pivotal movement of the boom.

The foot end of the boom 12 is pivoted at 13 to the rotating base, to provide for upward and downward movement thereof through a range such as defined by the positions indicated in Figures 1 and 3. Front compression gantry legs 14 extend upwardly and rearwardly from points adjacent the pivot axis 13 for the boom, to support the gantry headshaft 15. Rear tension gantry legs 16 extend downwardly from the gantry headshaft to be anchored to the rotating base.

Raising and lowering of the boom is controlled by the boom hoist cable 17 which is adapted to be reeved over sheaves 18 mounted on the gantry headshaft 15 (see Figure 4), the boom hoist cable ultimately being carried down into the cab for cooperation with a boom hoist drum. The cable 17 is also associated with sheaves 18' carried by a sling 19 which is supported from the point of the boom by means of sling cables 20. Ordinarily a number of runs of cable 17 are provided between sheaves 18 and 18'.

In accordance with the invention, the gantry shaft 15 carries pairs of upwardly projecting plates 21, which are apertured toward their upper ends to receive pivot trunnions 22 projecting in axial alignment with each other transversely of sleeves 23, one such sleeve being mounted in this manner adjacent each end of the gantry shaft 15. Each sleeve 23 cooperates with an assembly of telescopic boom stop members which are extended forwardly therefrom for attachment to the boom, as is illustrated in the drawings. Since the two assemblies of telescopic boom stop members are of the same construction, only one need be described.

The assembly is best shown in Figures 5 and 6 and includes an outermost tubular member 24 having a rear end cap 25 serving as a stop when

the cap abuts the rear end of sleeve 23 upon extension of the assembly. Tubular member 24 extends through and beyond sleeve 23 and is provided with an annular abutment 26 adapted to abut the forward end of sleeve 23 upon collapsing of the assembly when the boom swings upwardly. A second tubular member 27 extends into the forward end of member 24, the tube 27 having an annular abutment 28 which, upon collapsing of the telescopic assembly, is adapted to abut the fitting 29, which latter is secured to the forward end of the outermost tube 24. The tube 27 is restrained from being drawn completely out of tube 24 by an abutment sleeve 30 of diameter such as to engage the fitting 29. Sleeve 30, together with another sleeve indicated at 30a, serve to guide the telescopic movement of tube 27 in tube 24.

A third or innermost tube 31 extends into the forward end of tube 27, this third tube having a forked terminal fitting 32 pivotally connected with the apertured ear 33, which is welded or otherwise secured to the structure of the boom (see Figure 4). The terminal fitting 32 also serves as an abutment to restrict movement of tube 31 into tube 27, the fitting being arranged to engage the end of the hollow cap 34 on the forward end of tube 27. A sleeve abutment 35 on tube 31 cooperates with the hollow cap 34 in preventing movement of tube 31 completely out of tube 27. Another sleeve 35a cooperates with sleeve 35 to guide the telescopic movement of tube 31 in tube 27.

Toward the rear end of the assembly (the left end as viewed in Figures 5 and 6), a cushion device such as a compression spring 36 is arranged within the tube 24 to react between the inner end of tube 27 and the end of a spacer sleeve 37 disposed in the tube 24 just inside of the cap 25.

In the position of the parts illustrated in Figure 5, all of the elements of the assembly are collapsed or telescoped to the maximum possible extent and, from examination of this figure, it will be seen that the several abutments (26, 28 and 32) are all in engagement with the respective cooperating stop parts. In this condition, the spring 36 is compressed although there still remains slight spacing between the turns of the spring, so that the compression forces will be carried through the several abutments referred to. The showing of Figure 5 corresponds to the position of the boom illustrated in Figure 3.

In Figure 6, the assembly of telescoping tubes is illustrated extended to the maximum possible degree, which corresponds to a boom position somewhat lower than that illustrated in Figure 1. In the preferred construction, the stop assemblies are arranged to have a degree of extension sufficient to prevent the parts from being placed under tension even when the boom is lowered to the maximum limit of the normal operating range. Thus it is contemplated that downward movement of the boom shall normally be restrained only by the action of the boom hoist cable, but that the stop assemblies will serve, in compression, to cushion and limit extreme upward movement of the boom under certain abnormal conditions.

The connection of the boom stops to the gantry shaft 15 is of advantage for a number of reasons, including the fact that the gantry shaft is so located as to constitute a particularly effective and well braced reaction point for the boom stops when the latter act in compression to limit upward movement of the boom.

I claim:

1. In a load handling machine having a gantry and a boom, the latter being mounted for upward and downward swinging movement, mechanism for arresting upward swinging movement of the boom comprising a sleeve pivotally mounted on the gantry, a tubular member slidably in said sleeve, a compression member telescopically associated with the tubular member and connected with the boom, first stop means on the tubular member positioned to engage the sleeve, and second stop means on the compression member positioned to engage the tubular member, both of said stop means being operative in the upper range of swinging of the boom to limit telescopic movement of the compression member into the tubular member and sliding movement of the tubular member into the sleeve, whereby said members act in compression to limit the range of upward swinging of the boom.

2. In a load handling machine having a gantry and a boom, the latter being mounted for upward and downward swing movement, mechanism for arresting upward swinging movement of the boom comprising three telescopically associated members, one pivotally connected with the boom, one pivotally connected with the gantry and the third being telescopically intermediate and serving to interconnect the first two, stop means at the outer end of the internal member positioned to engage the outer end of the intermediate member upon telescoping of the internal member into the intermediate member when the boom moves upwardly, and stop means intermediate the ends of the intermediate member positioned to engage the free end of the external member upon telescoping of the intermediate member into the external member when the boom moves upwardly, whereby said external member acts in compression in limiting the upward swinging of the boom.

3. In a load handling machine having a gantry and a boom, the latter being mounted for upward and downward swinging movement, mechanism pivotally connected at one end to the boom and at the other to the gantry for arresting upward swinging movement of the boom, said mechanism comprising a plurality of telescopically associated members, stop means on one telescopic member positioned to engage the end of a second member into which it telescopes when the boom swings upwardly, and a yielding device connected with one of said members and adapted to react upon the other during the minor fraction of the upward movement of the boom which precedes engagement between said stop means and said end, whereby said second member acts in compression in positively limiting the range of upward swinging of the boom.

WILLIAM M. HUSTON.
